(57) **CLAIM**

The ornamental design for a concrete fire bowl as shown and described.

DESCRIPTION

FIG. 1 is a top perspective view of the concrete fire bowl embodied in the present invention;

FIG. 2 is a top view of the concrete fire bowl from FIG. 1; FIG. 3 is a bottom view of the concrete fire bowl from FIG. 1;

FIG. 4 is a side view of the concrete fire bowl from FIG. 1; FIG. 5 is as end view of the concrete fire bowl of FIG. 1; and, FIG. 6 is a side perspective view of the concrete fire bowl of FIG. 1.

The dash-dash-dash broken line shown in FIG. 1, FIG. 2, FIG. 3 and FIG. 6 is included for the purpose of illustrating environmental context and forms no part of the claimed design.
